UNITED STATES PATENT OFFICE.

ISADORE M. SAVIT, OF MILWAUKEE, WISCONSIN.

HAT-PIN.

938,277.

Specification of Letters Patent.

Patented Oct. 26, 1909.

Application filed February 1, 1909. Serial No. 475,389.

To all whom it may concern:

Be it known that I, ISADORE M. SAVIT, a citizen of the United States, residing at Milwaukee, county of Milwaukee, and State 5 of Wisconsin, have invented new and useful Improvements in Hat-Pins, of which the following is a specification.

My invention relates to improvements in hat pins, and it pertains to that class of 10 ornamental pins, which are adapted to be used both for ornament and for holding a lady's hat in place when worn.

The construction of my invention is explained by reference to the accompanying 15 drawings, in which—

Figure 1 is a side view. Fig. 2 is a vertical section. Fig. 3 is also a vertical section of a modified form; and Fig. 4 is a perspective view thereof, showing the head inclosing cover as it appears when it is being drawn and secured together around the pin.

Like parts are identified by the same reference numerals throughout the several views.

1 represents an ordinary hat pin provided 25 with a hard metallic or composition head 2 of ordinary construction.

3 is a spherical ball which is preferably made of cork, wood, or other light material. In the preferred form, the ball 3 is made 30 in two parts 4 and 5, substantially hemispherical in shape, when central cavities 6, 6, are formed in such parts for the reception of the head 2 of the pin. When this is done, the pin 1 is inserted centrally through the 35 part 5 and forced down until the head 2 is brought into the cavity of such part, when the other hemispherical part 4 is placed against said head, as shown in Fig. 2, when said hemispherical parts 4 and 5 are permanently secured together by the fastening 40 pins 7, 7. When the parts 4 and 5 have thus been secured together, they are entirely surrounded by the flexible fur like cover 8, which cover is pressed into a sack shape, 45 shown in Figs. 2 and 3, when a gathering cord 9 is inserted backwardly and forwardly in a zigzag course through the gathered edges of the mouth of the sack shaped cover, as shown. When this is done, the respective 50 ends of the cord 9 are drawn and secured together around the pin 1, whereby the cover 8 is securely retained in place.

10 represents the fur of the cover which is caused by the convex shape of the interior

to radiate in all directions around the central head 2, whereby the fastening cord 9 is entirely covered up and excluded from view. The pin 1, which is thus provided with a fur like covered head, is more especially adapted to be used for securing fur 60 hats and caps to the head of the wearer, while the fur inclosing cover gives to the same a neat, rich, and ornamental appearance.

In the modified form shown in Fig. 3, the 65 spherical member 11 is formed of a single piece and is provided on its upper side with a socket or recess 12 for the reception of the head 2, which is inserted in said socket, while the pin extends through the lower side of 70 said member 11 and said pin is retained in place by the metallic clamping band 13, which is provided with an aperture 14 for the reception of the pin, while the ends of the clamping band are secured together below 75 the head 2 of the pin by the nail 15. When the member 11 is thus secured to the pin, the same is surrounded with the fur cover 8, the same as heretofore described in connection with Fig. 2. While I have referred to the part 8 as being a fur cover, I do not wish to limit myself to the use of fur 80 for such cover, as it is obvious that many imitations of fur may be substituted therefor.

Having thus described my invention, what 85 I claim as new, and desire to secure by Letters Patent is—

1. The combination with a pin provided with a rigidly affixed head of ordinary construction, with an inclosing spherical 90 shaped ball, means for securing said ball to said head, and a flexible inclosing cover having a fur like exterior surface.

2. The combination with a pin provided with a rigidly affixed head of ordinary construction, with an inclosing spherical shaped ball, means for securing said ball to said head, and a flexible inclosing cover having a fur like exterior surface, said cover being sack shape in form and provided at 100 its mouth with a gathering cord by which the mouth of the cover is drawn and secured together around said pin.

3. The combination with a pin provided with a rigidly affixed head of ordinary construction, with an inclosing spherical shaped ball formed in two hemispherical parts rigidly secured together around the 105

head of said pin by transversely arranged fastening pins and an inclosing sack shaped flexible cover having a fur like exterior surface, the mouth of which is provided with a gathering cord inclosing and adapted to be secured together around said pin, all substantially as and for the purpose specified.

In testimony whereof I affix my signature in the presence of two witnesses.

ISADORE M. SAVIT.
